UNITED STATES PATENT OFFICE

ARTHUR SKEFFINGTON, OF BLACKHEATH, LONDON, ENGLAND.

APPARATUS FOR HANDLING INVALIDS, DEFORMED PERSONS, OR THE LIKE.

1,085,879.

Specification of Letters Patent.

Patented Feb. 3, 1914.

Application filed April 14, 1910. Serial No. 555,532.

To all who n it may concern:

Be it known that I, ARTHUR SKEFFINGTON, a subject of the King of England, residing at Blackheath, in the county of London, England, have invented certain new and useful Improvements in Apparatus for Handling Invalids, Deformed Persons, or the like, of which the following is a specification.

10 This invention is for improvements in or relating to apparatus for handling invalids, deformed persons or the like (hereinafter referred to as the patient) and has for its object to enable a patient upon a bed to be readily moved.

15 This invention relates to the type of apparatus wherein a roller operated draw-sheet or the like is employed to move the patient the roller apparatus being carried by the frame of the bed. It has been proposed heretofore to variously situate such rollers, but none of the constructions so far proposed appear to offer the best advantages from the point of view of efficiency and simplicity combined. The various forms of apparatus so far suggested have been of a complicated character and this it is believed has prevented their being generally known on the market.

20 The present invention is intended to provide an apparatus that is of the same type as those referred to, but that dispenses with all auxiliary devices and is in itself extremely simple.

25 This invention consists in providing apparatus of the type described that for moving the patient toward the head of the bed has only one roller arranged on the inner side of the upright frame at the head of the bed and a draw-sheet suspended free from it. A second roller similarly arranged on the inside of the end frame at the foot of the bed may be employed and the other end of the draw-sheet may be attached to it so that 30 by pulling the draw-sheet tight between them the patient may be lifted bodily off the bed. This constitutes an extremely simple apparatus as the draw-sheet being free does not pass under any guide rollers or over any 35 intermediate lifting rollers but passes direct to the single or to the two rollers that constitute both the lifting and winding rollers and the situation of these between the upright frames of the bed, renders the whole 40 apparatus compact.

Other details of the apparatus constitute

part of this invention and such are herein-after fully described and the novel features pointed out in the claims.

In the accompanying drawings:—Figure 60 1 is a perspective view showing a bed fitted with apparatus constructed according to one method of carrying out this invention; Fig. 2 shows a detail of Fig. 1 on a larger scale for the sake of clearness; Fig. 3 is a perspective view of a detail of Fig. 1; Fig. 4 is a front elevation of a modified form of apparatus; Fig. 5 is a diagrammatic view showing in side elevation another arrangement of apparatus constructed according to 70 this invention, and Fig. 6 is a front elevation of yet another modification according to this invention.

Like letters indicate like parts throughout the drawings.

75 Secured to the uprights A of the head of the bed are four rods B B¹ and C C¹. The rods B B¹ are placed on opposite sides of the posts A and are clamped to the posts by links B² having set screws B³. The rods C C¹ are also placed on opposite sides of the posts and below the rods B B¹ being held in place by links C² and set screws C³. The rods may be clamped direct to the posts A if desired, but preferably wood blocks D 80 are interposed. These blocks have a vertical groove D¹, Fig. 3, on one face shaped to receive the posts and a horizontal groove D² on the opposite face to receive the rods. Carried on the rods B and C are two brackets E and E¹. The bracket E is placed on the ends of the rods that project beyond the post A on the near side of the bed as shown in the figure, but the bracket E¹ is situated near the post on the far side of the 85 bed but on the near side of the post. The brackets are secured by set screws E². Each bracket has a bearing to receive one end of the lifting and winding roller F, the ends of the roller being journaled where they enter 90 the bearings. The journaled end of the roller that rests in the bearing provided in the bracket E extends beyond the bearing and carries a worm wheel F¹ and the bracket E is provided with ears E³ which support 95 a spindle F³ carrying a worm F² that meshes with the wheel F¹. The end of the spindle F³ is squared and receives a crank handle F⁴. Extending over the bed is a draw-sheet G 100 which may lie under the sheet or other covering upon which the patient lies and one end of this sheet is firmly attached to the roller 105 110

F, but hangs freely therefrom. The operation of this part of the apparatus is as follows:—It is well known that patients in a weak condition gradually slip down from the head of the bed and considerable effort is needed to replace them. By means of this apparatus, however, it is only necessary to turn the handle F⁴ so that the roller will be rotated in such direction as to pull upon the end of the sheet G and wind it on to the roller. The patient will thus be moved over the bed in a horizontal position with very little effort as the purchase given by the worm F² and the worm-wheel F¹ is very considerable. It will be seen that in addition to moving the patient toward the head of the bed, the apparatus if placed high enough may be employed to raise the patient into a sitting position, the winding upon the sheet being merely continued for this purpose after the head of the patient has been brought to the head of the bed.

The rods B B¹ and C C¹ are convenient for securing the apparatus to the frame of the bed as they can be readily clamped on to any bed provided they are of sufficient length to extend from one post to the other and the wood blocks may be stocked in various sizes so that blocks having the groove D¹ shaped to the size of the post which the apparatus is to be applied to may always be sent out with the mechanism. Obviously where the posts are square, as for example in a bedstead having a wooden head, the blocks may be dispensed with and even where the posts are round, a sufficient grip can be obtained without the use of blocks.

According to a modification of this invention a second roller H is mounted at the opposite end of the bed. The roller is carried by rods H¹ and brackets H², which parts are the same as those already described with reference to the roller F and a worm and worm-wheel H³ H⁴ is provided for operating the roller. The squared end H⁵ of the spindle of the worm H³ may be made the same size as the squared end of the spindle F⁴ of the worm F² so that the crank handle F⁴ can be used to operate either worm. The roller H has rigidly secured to it the lower end of the draw-sheet G and can be used for returning the draw-sheet after it has reached the limit of its movement toward the head of the bed. The same roller however may be employed in conjunction with the roller F to raise the patient vertically from the bed while in a lying position and maintaining the patient vertically above the bed while the latter is re-arranged. All that is necessary for this is that one or both of the rollers shall be rotated to take up all the slack of the draw-sheet and haul the sheet tight so that it is extended from the top of one roller to the top of the other, as shown in chain lines at G¹. The patient can thus

be lifted by the draw-sheet while still in a lying position and access can be had to the bed for the purpose of re-arrangements.

In Fig. 4 two wooden supports J are shown connected by a tie-piece J¹. The wooden supports provide bearings for a roller K and one of the supports has rotatably mounted upon it the worm gearing K¹. It will be seen that the supports J can be strapped to the posts A of the bedstead instead of using the rods B B¹ and C C¹.

In some cases it may be desirable to use an endless draw-sheet. Such an arrangement is shown diagrammatically in Fig. 5 where the endless sheet L passes over rollers L¹ L², one of which is situated at the head of the bed and the other at the foot of the same. In this case the roller L¹ is rotated by the gearing for the purpose of advancing the draw-sheet and in order that it may grip the sheet a second roller L³ may be mounted above it and made to bear forcibly upon the sheet and roller L¹ by means of springs L⁴, these engage bearing blocks L⁵ that are free to slide in a supporting bracket L⁶ which would in this case take the place of the bracket E E¹.

If desired the apparatus may be arranged to swing about a pivot the axis of which is parallel with the longitudinal axis of the bed. Such an arrangement is shown in Fig. 6 where a wooden or other support M is secured by any convenient means to the frame of the bed. Pivoted at M¹ to the board M is a second board M² carrying the roller N and operating gear N¹. The draw-sheet can thus be wound on to the roller as before and by swinging the board M² about the pivot M¹ so as to tilt the roller N the end of the draw-sheet attached to the roller is similarly tilted and the patient thereby turned over on either side as required for comfort or other purposes.

It will be appreciated that if the patient is lying in the center of the draw-sheet there will be a tendency to draw the sides of the sheet inward, and to counteract this tendency the roller is preferably made of greater diameter in the center than at the ends, as is clearly shown in Fig. 1.

It will be observed that by the provision of the roller-supporting brackets and the means for detachably clamping them to the upright frame or frames of the bed, said brackets can be adjusted vertically on said frame or frames, thus enabling the roller or rollers to be positioned at various heights, which is a decided advantage over those constructions where the rollers have no vertical adjustment.

What I claim as my invention and desire to secure by Letters Patent is:—

1. In apparatus for handling invalids upon a bed, the combination with a bedstead, of transverse rods in pairs whereof

one is situated inside and one outside the end frame, clamps drawing each pair of transverse rods together and securing them on the end frame, a bracket extending between and slipped upon the inner rods of an upper and lower pair of transverse rods and projecting inward from the end frame toward the other end of the bed, a worm gear on said bracket, another bracket slipped on said inner rods, means for clamping said brackets when adjusted on said rods, bearings in said brackets, a roller extending transversely of the bed and mounted in said bearings, a worm wheel on said roller engaging said worm gear, and a draw sheet secured to said roller and extending over the bed.

2. In apparatus for handling invalids upon a bed, the combination with a bedstead, of transverse rods in pairs whereof one is situated inside and one outside the end frame, and whereof both project at one end beyond the end frame, clamps drawing each pair of transverse rods together and gripping them upon two upright members on the end frame, a bracket extending between and slipped upon the projecting ends of the inner rods of an upper and lower pair of transverse rods and projecting inward from the end frame toward the other end of the bed, a worm gear on said bracket, another bracket slipped on said inner rods, means for clamping said brackets when adjusted on said rods, bearings in said brackets, a roller extending transversely of the bed and mounted in said bearings, a worm wheel on said roller and secured to said roller and extending over the bed.

30

35

wheel on said roller engaging said worm gear, and a draw sheet secured to said roller and extending over the bed.

3. In apparatus for handling invalids upon a bed, the combination with a bedstead, of transverse rods in pairs whereof one is situated inside and one outside the end frame, two-part blocks embracing one of two upright members on the end frame and interposed between the transverse rods and said upright members, clamps drawing each pair of transverse rods together and gripping them on said blocks and on said upright members, a bracket extending between and slipped upon the inner rods of an upper and lower pair of transverse rods and projecting inward from the end frame toward the other end of the bed, a worm gear on said bracket, another bracket slipped on said inner rods, means for clamping said brackets when adjusted on said rods, bearings in said brackets, a roller extending transversely of the bed and mounted in said bearings, a worm wheel on said roller engaging said worm gear, and a draw sheet secured to said roller and extending over the bed.

In testimony whereof I have signed my name to this specification in the presence of two subscribing witnesses.

ARTHUR SKEFFINGTON.
